HOLDER FOR CARBON ROLLS

Lester K. Fleischmann, Chicago, Ill.

Application October 13, 1954, Serial No. 462,074

7 Claims. (Cl. 197—126)

This invention relates to carbon holders for writing machines, and more particularly to a carbon holder for supporting carbon rolls and their unwound carbons in proper alignment between strips of continuous form stationery.

Carbon holders are normally mounted for longitudinal movement upon a forms carrying device which in turn is secured to the rear of a writing machine so that the forms carrying device can move laterally with the carriage of the writing machine during a typing operation. A number of carbon rolls are each supported by the carbon holder between adjacent strips of continuous form stationery with an unwound portion extending from each roll forwardly around the platen in registry with the stationery. The forms carrying device extends rearwardly of the writing machine, and the movable parts thereof permit some play to cushion the shock from normal operation, and also abrupt stops, of the carriage. On occasion the forms carrying device gets out of lateral alignment with the platen, and when the unwound portions of the carbons being used are moved rearwardly for use between the next following form length of stationery, the carbon may also slide laterally out of proper alignment with the adjacent strips of continuous form stationery. The structure of the present carbon holder avoids such difficulties.

The primary object of the present invention is to provide a new and improved carbon holder for supporting one or more carbon rolls between strips of continuous form stationery.

An important object is to provide an improved carbon holder for maintaining the forwardly extending carbon strip in proper lateral alignment between adjacent strips of continuous form stationery.

Another object is to provide a removable carbon roll supporting structure which will facilitate the replacement of a carbon supply roll.

A further object is to provide swingably mounted carbon roll supporting structures which are held against shifting laterally of the carbon holder base, and which have spacer members to provide adequate clearance for a carbon roll and a stationery strip between each adjacent pair of supporting structures.

The invention is illustrated in a preferred embodiment in the accompanying drawings, in which:

Fig. 1 is a top plan view of the carbon holder;
 Fig. 2, an elevational view of the holder;
 Fig. 3, a sectional view taken as indicated on line 3—3 of Fig. 1;

Fig. 4, an end elevational view of the carbon holder;
 Fig. 5, a sectional view taken as indicated on line 5—5 of Fig. 1; and

Fig. 6, an enlarged broken sectional view taken as indicated on line 6—6 of Fig. 4.

In the embodiment illustrated, the carbon holder may be attached to a carrying plate 10 of a forms carrying device (not shown) by a pair of hooks 11 struck downwardly from a channel-shaped base member 12 on the carbon holder. The hooks 11 are of a size to enter aper-

2

tures 13 in a pair of bosses 14 which extend upwardly from the carrying plate 10. A latch member 15, of a type more fully described in my co-pending application, Serial No. 265,113, filed January 5, 1952, may be pivoted to the carrying plate 10 and, when turned into abutment with an end of the base member 12, as shown in Fig. 1, locks the hook members 11 beneath the marginal portions adjacent the apertures 13 in the bosses 14.

A pair of upwardly extending spaced supports 16 and 17 are secured to the base member 12 near its opposite ends. Each of the spaced supports is provided with a plurality of similarly spaced, rearwardly opening slots 18, and a spring wire closure member, 19 and 20, respectively. Each of the closure members is adapted to be swung into one of the upright channels 21 and 22, respectively, in the spaced supports and snapped over the nodes 23 and 24 at the top of each of the supports.

A plurality of similar carbon roll supporting structures, each generally designated 25, extend between and are secured to the upright supports 16 and 17. Each of the structures 25 preferably includes an elongated flat metal mounting plate 26 for receiving a carbon roll, generally designated 27. Each mounting plate is pivotally supported on a wire frame structure in turn swingably secured in the slots 18 of the upright supports 16 and 17. Each of the mounting plates 26 is maintained in a generally horizontal position when in use, and is preferably provided with a pair of scales 26a so that a new carbon roll can be placed about the mounting plate 26 in the same position as the carbon roll being replaced. The mounting plate has a spacer block 28 secured to each of its opposite end portions to provide adequate clearance for the carbon rolls 27 and strips of continuous form stationery 27a between adjacent mounting plates 26. In addition, the spacer blocks 28 provide bearing surfaces for a pair of arms 29 of the wire frame.

The arms 29 preferably swingably secure the mounting plate 26 to the upright supports 16 and 17. Each of the arms is bent inwardly to form a trunnion 30 at its forward end of a size to fit within a well in one of the spacer blocks 28, and bent outwardly to form a trunnion 31 at its rearward end to fit within a slot 18 in the upright supports. To place the trunnions 31 in a pair of corresponding slots 18, the closure members 19 and 20 are first swung down from their operative position in the channels 21 and 22. When the closure members are again swung into the position illustrated in Figs. 1 and 2, they lock the trunnions 31 securely within the forward end of the slots 18 and prevent the trunnions 31 from moving longitudinally of the carbon holder.

Each of the arms 29 has an outwardly offset portion 29a which abuts the inner surfaces of the upright supports 16 and 17 to prevent each of the supporting structures 25 from shifting laterally of the carbon holder when in use. In addition, each of the arms 29 preferably has an inwardly turned, U-shaped projection 32 adapted to fit within opposite ends of a hollow cross bar 33 which adds strength and stability to the supporting structure 25. However, the supporting structures 25 still remain sufficiently flexible so that when one end of a mounting plate 26 is raised, its opposite end may not be raised to the same degree.

Mechanism is also provided to afford tilting adjustment for the supporting structures 25 of the carbon holder. As herein shown, this mechanism comprises a pair of supporting levers, generally designated 34, journaled in the upright supports, 16 and 17, and a pair of adjusting studs 35, each eccentrically mounted by an eccentric mounting shaft 35b passing through an upright support. Each of the adjusting studs 35 may be provided with a slot in its outer face so that a stenographer may use a coin in the slot to turn each adjusting stud and vary its

position on an upright support. While two levers are shown, it is clear that a single lever will adequately perform the tilting function. In such an arrangement, one end of the structures 25 would be provided with a stationary support while a single lever at the other end would raise or lower that end with respect to the horizontal. Since the levers function identically, a description of the operation of one lever will suffice:

The lever 34, preferably made of wire, has an outwardly bent medial portion forming a journal shaft portion 36 resting in an opening near the lower end of the upright support 17. The fulcrum or journal shaft portion 36 divides the lever 34 into a pair of lever arms, 37 and 38. Lever arm 37 extends generally rearwardly adjacent the outer face of the upright support 17. Lever arm 38 extends generally forwardly of the carbon holder, and terminates in a hooked end portion 39 which is normally in supporting engagement with the arm 29 on the lowermost of the carbon roll supporting structures 25. The weight of the supporting structures 25 on the lever arm 38 maintains the lever arm 37 constantly in engagement with the underside of an annular depression 35a in the stud 35 on the upright support 17.

To operate the tilting mechanism, the stud 35 is turned so that it moves, for instance, downwardly of the support 17. This depresses the lever arm 37 and raises the lever arm 38 causing the mounting plate 26 to tilt slightly from its generally horizontal position. By turning the stud 35 in the opposite direction, the lever arm 37 is raised lowering lever arm 38 which is depressed by the weight of the supporting structure 25.

The purpose of tilting the mounting plate 26 of the carbon holder is to maintain the free end of the carbon unwound from the carbon roll in proper lateral alignment between adjacent strips of continuous form stationery. During a typing operation, the carbon holder is advanced longitudinally of the forms carrying device toward the writing machine as one or several form lengths are being typed. Ultimately the carbon holder reaches its forward limit. The carbon holder and carbon then must be retracted so that the carbon can be used again between following form lengths in the strip of continuous form stationery. It is during this retraction of the carbon that its lateral alignment must be carefully preserved. If the forms carrying device is slightly askew due to the looseness of its attachment to the writing machine, the carbon being flexible, may also travel laterally of the stationery strips as it is withdrawn. The strips of stationery of course will not be affected because they are held upon the platen of the writing machine. To correct the lateral travel of the carbon, an end of the carbon roll 27 on the mounting plate 26 is raised or lowered, as the case may be, so that the carbon is retracted in proper lateral alignment between the stationery strips. So long as the carbon roll 27 is tilted from the horizontal, the tilting mechanism used may vertically adjust an end of the mounting plate 26 alone or it may tilt the entire carbon holder with respect to the horizontal.

In using the present carbon holder, it is preferred that a mounting plate be positioned beneath the bottom, and above the top, stationery strip. Such an arrangement has been found to provide added tension in the lowermost and uppermost strip so that neither will advance too rapidly, or too slowly, about the platen of the typewriter.

Another feature of the present invention becomes apparent when the carbon holder is being used with a plurality of carbon rolls and stationery strips. As the carbon holder is advanced toward the writing machine, the angle between the uppermost strips and the point of entry about the platen is greatly increased. However, since each of the mounting plates 26 is pivotally secured to the arms 29, the plates 26 tip downwardly to minimize binding between the strips and the forward edges of the mounting plates.

In order to replace a carbon roll, one of the arms 29

is sprung outwardly permitting the old carbon roll to be slipped off. The operator may note the position of the old carbon roll with respect to the scale 26a, and a new carbon roll is slid over the mounting plate to the proper position and may be secured in place by a tab 27b provided with a pressure sensitive adhesive. Trunnion 30 is then replaced in its spacer block 28.

To add a new strip of carbon between the stationery strips, the old carbon strip is merely torn off with the form lengths which have been typed. Each mounting plate is then flipped over two or three times to unroll and provide a new carbon supply after which normal typing operation can once more proceed.

The foregoing detailed description is given for clearness of understanding only and no unnecessary limitations should be understood therefrom, for some modifications will be obvious to those skilled in the art.

I claim:

1. A carbon holder for supporting a carbon roll between strips of continuous form stationery in a writing machine, comprising: a base member adapted to be secured to the writing machine, said base member having a pair of upwardly extending spaced supports; a carbon roll supporting structure extending between and secured to said spaced supports to hold a carbon roll in a generally horizontal position; and mechanism for adjustably tilting said carbon roll supporting structure to maintain carbon unwound from the carbon roll in proper lateral alignment between the strips of continuous form stationery.

2. A carbon holder for supporting a carbon roll between strips of continuous form stationery in a writing machine, comprising: a base member adapted to be secured to the writing machine, said base member having a pair of upright spaced supports; a carbon roll supporting structure extending between and secured to said spaced supports for holding the carbon roll in a generally horizontal position, said supporting structure including a mounting plate for receiving and supporting the carbon roll, and an arm secured to each upright support and to an end portion of the mounting plate; a supporting lever fulcrumed on said base and extending outwardly into supporting engagement with one of said arms; and manually operable mechanism for raising and lowering the lever so as to tilt the carbon roll mounting plate and maintain carbon unwound from the carbon roll in proper lateral alignment between the strips of continuous form stationery.

3. A carbon holder as specified in claim 2, in which the manually operable mechanism comprises an eccentrically mounted stud on one of said upright supports, said stud normally contacting a portion of the supporting lever whereby rotation of said stud imparts movement to said lever to provide tilting adjustment of the mounting plate.

4. A carbon holder as specified in claim 2, in which a portion of each of the arms abuts its respective spaced support to prevent lateral shifting of the carbon roll supporting structure.

5. A carbon holder as specified in claim 2, in which each of the spaced supports has a plurality of similar rearwardly opening slots and a spring wire closure member to close the open ends of said slots; and the arms of the supporting structure are journaled in corresponding slots in their respective upright supports to swingably mount said supporting structure, each of said closure members holding one of said arms securely within its respective slot.

6. A carbon holder for supporting a plurality of carbon rolls between strips of continuous form stationery in a writing machine, comprising: a base member adapted to be secured to the writing machine, said base member having a pair of upright spaced supports; a plurality of carbon roll supporting structures swingably mounted in said spaced supports, each of said supporting structures including a mounting plate for receiving and supporting a

carbon roll, and a light weight wire frame pivotally supporting said mounting place, said frame being swingably received in said upright supports, a portion of the wire frame abutting said upright supports for maintaining lateral alignment of the carbon roll supporting structure; and a side support positioned at each side of said carbon roll supporting structures, said side supports engaging and supporting said structures in a predetermined position, one of said side supports being manually adjustable in elevation for tilting the carbon roll supporting structures to maintain carbon unwound from the carbon rolls in proper lateral alignment between the strips of continuous form stationery.

7. A carbon holder for supporting a plurality of carbon rolls between strips of continuous form stationery in a writing machine, comprising: a base member adapted to be secured to the writing machine, said base member having a pair of upright spaced supports; a plurality of carbon roll supporting structures swingably mounted in superposed relation on said spaced supports, each of said supporting structures including an elongated, carbon roll mounting plate having opposite end portions, a spacer block secured to each of said end portions to provide clearance between superposed mounting plates, and a

5

10

15

20

pair of arms each pivotally secured at one end to the spacer block and at the other end to a spaced support; and a pair of supporting levers, each fulcrumed on said base member to form two lever arms, the first of said lever arms extending forwardly into supporting engagement with the bottom supporting structure, and the second of said lever arms extending rearwardly adjacent their respective upright supports, the engagement of each of said first lever arms and said bottom supporting structure normally tending to rotate each of said second lever arms; and a stud eccentrically mounted on each of the upright supports and contacting each of the second lever arms to arrest their rotative movement, the turning of one of said studs causing pivotal movement of a supporting lever so as to tilt an end portion of said mounting plates to maintain carbon unwound from the carbon rolls in proper lateral alignment between strips of continuous form stationery.
